UNITED STATES PATENT OFFICE.

WILLIAM J. DOOLEY, OF NEW YORK, N. Y.

GAS-RETORT LID.

SPECIFICATION forming part of Letters Patent No. 236,999, dated January 25, 1881.

Application filed June 3, 1880. (No model.)

To all whom it may concern:

Be it known that I, WILLIAM J. DOOLEY, of the city, county, and State of New York, have invented a new and useful Improvement in 5 Gas-Retort Lids, of which the following is a specification, reference being had to the accompanying drawings, forming part of the same.

Figure 1 is a front end view of a gas-retort mouth-piece and lid containing my invention, 10 the lid being closed. Fig. 2 is a top view of same with a portion of the flange of the mouth-piece cut away. Fig. 3 is a front end view of same with the lid swung open, presenting to view the rear surface of the lid; and Fig. 4 is 15 a central section of a detached part, particularly described hereinafter.

My invention relates to the securing of the lid or door to the mouth of the gas-retort, such as is ordinarily used in the manufacture of 20 illuminating-gas; and it consists in the devices hereinafter described and claimed, whereby the lid is readily and conveniently closed and forced against the mouth-piece, so as to form a tight joint, and at pleasure readily and conveniently detached and removed or swung 25 open.

A is the mouth-piece, similar to those in general use. Its form and construction being well known in the art, a description of them 30 is unnecessary.

B is the lid, also of the usual form. It is hinged to the mouth-piece, as shown in the several figures, it being desirable that when the lid is swung against the mouth-piece to 35 close it, contact between the lid and the mouth-piece entirely around the lid should take place at the same instant, and not at a single point first; otherwise the point of first contact is liable to become worn, and thereby the gas-tight joint between the lid and mouth-piece be 40 impaired. To secure this uniform contact I arrange for an adjustment of the lid on its hinge. This I do by forming the strap C of the single hinge to which the lid is fastened 45 of two arms, *a* and *b*, the end of *a* being screwed to the lid near the top and the end of *b* near the bottom. The opposite end of the strap is screwed to the lid at *c*. Small bosses are formed on the lid under the ends of *a* and *b* and at *c*, for 50 the strap to rest upon, and into which the screws enter, when, by the use of thin wash-

ers placed between the strap and the bosses, the lid may, it is evident, be adjusted on the hinge so that when swung to it will strike against the mouth-piece all around at the same 55 instant.

I will now describe my peculiar devices by which I force the lid against the mouth-piece to make a tight joint.

d d' are two lugs that project inward on opposite sides of the interior of the mouth-piece. Near its mouth is a bar, *D*, so hinged to the rear face of the lid, as seen plainly in Fig. 2, that when allowed to swing downward it will be below the lugs *d d'*. To the center of this 65 bar is pivoted a rod, *e*, which passes through the lid, and is provided with a screw-thread and hand-nut *f* on its outer end. The arrangement of the parts is such that when the bar *D* is dropped down and the lid swung against 70 the mouth-piece the bar will pass under and to the rear of the lugs *d d'*. Then by turning down the nut *f* and thus drawing the rod *e* out the bar *D* is swung upward and behind the lugs *d d'*, so that its ends will engage the said 75 lugs. By turning the said nut down still farther the lid is pressed forcibly against the mouth-piece. To release the lid it is only necessary to turn back the nut, when the bar will, by its own weight, drop down away from and 80 below the lugs *d d'*, when the lid can be swung open.

It is evident that provision must be made for a slight vertical movement of the inner end of the rod *e*, which must rise and fall with the 85 bar *D* as the latter swings on its hinges. To this end the hole in the lid through which the said rod passes is made large enough to permit such movement. A boss, *g*, is formed on the lid, the said hole passing through the boss. 90 On the outer end of this boss is a semi-cylindrical concavity, into which fits a bushing-piece, *h*, that is convex on one face to fit the boss and plane on the opposite face. The rod *e* passes through this bushing, and the hand-nut *f*, which has on its inner face a boss to match the bushing, fits down upon the bushing. It is obvious that this arrangement of parts will permit the movement of the rod *e* before mentioned, and at the same time secure 95 a gas-tight joint at the aperture in the lid 100 through which the rod passes.

What I claim as my invention, and desire to secure by Letters Patent, is—

1. The mouth-piece A, provided with the lugs *d d'*, and the lid B, to the rear face of which is hinged the bar D, that has pivoted to it the screw-rod e, provided with the hand-nut f, the said bar being arranged to swing down below the said lugs by turning back the nut f and pushing in the rod e, and to be swung up behind the lugs *d d'* and to engage therewith by turning down the said nut and thereby drawing said rod e out, all constructed and combined to operate as and for the purpose described.

15 2. The combination, with the lid B, of the

bar D, the rod e, hand-nut f, and bushing-piece h, as and for the purpose specified.

3. The mouth-piece A and lid B, hinged thereto by a single hinge, the strap C of which is formed with the two arms *a* and *b*, and secured to the lid by screws *a'*, *b'*, and *c*, the lid being adjustable on the said strap by means of thin washers placed between the strap and bosses on the lid, as and for the purpose described. 20
